UNITED STATES PATENT OFFICE.

CHARLES C. KINSMAN, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

DRAFT-ARM FOR RAILWAY-CARS.

1,300,847.

Specification of Letters Patent. Patented Apr. 15, 1919.

Application filed September 18, 1914. Serial No. 862,295.

To all whom it may concern:

Be it known that I, CHARLES C. KINSMAN, a citizen of the United States, and resident of Chicago, county of Cook, and State of Illinois, have invented certain new and useful Improvements in Draft-Arms for Railway-Cars, of which the following is a specification, and which are illustrated in the accompanying drawings, forming a part 10 thereof.

The invention relates to draft arms for railway cars adapted to transmit to the car the stresses of draft and buffing, and to strengthen its underframe.

15 One form of construction by which these objects are attained is hereinafter described and is illustrated in the accompanying drawings, in which—

20 Figure 1 is a detail longitudinal vertical section of a car showing the improved draft arm in elevation;

Fig. 2 is a cross section on the line 2—2 of Fig. 1; and

25 Fig. 3 is a sectional view on the line 3—3 of Fig. 1.

The improved draft arm comprises a body portion 10 provided with the usual draft lugs, as 11, 12, arranged and constructed as may be required to coöperate with the draft 30 gear intended to be used.

The arm is provided with a rearward projection extending beyond the body bolster of the car, the top and bottom members of which are represented, respectively, at 13, 35 14.

This rearward extension of the draft arm may be described as comprising two sections, a lower section 15 which extends through the bolster, and an upper section 16 which arches over it. Differently described, 40 the extension may be said to be provided with an aperture 17 through which the bolster, or a portion thereof, viz.—the upper plate 13, extends.

The draft arm is adapted for use in connection with what is known as a plate bolster, the upper and lower members 13, 14, of which are flat wrought metal plates, the upper one being straight from end to end and the lower one being bowed upwardly.

50 at its ends, the two forming a truss. In such bolsters the upper member is usually provided, as shown, with depending lugs, as 18, at its ends, against which lugs the ends of the lower member 14 abut. The aperture 55 17 in the draft arm is of the same width as

the bolster member 13, and is of sufficient height to permit the insertion therethrough of the lug 18. The lower face of the portion 15 of the draft arm extension is recessed, as shown at 19, to receive the truss member or 60 plate 14.

The upper section 16 of the draft arm extension is adapted to lie against a side face of one of the car sills 20, shown in the drawings as being of wood and the lower section 15 is preferably provided with lateral flanges, as 21, 22, 23, as many as may be deemed advisable for securing the requisite strength, the top and bottom flanges 21, 23, forming bearing surfaces for the bolster 70 members 13, 14, the upper one of these members being securely held between the flange 21 and the lower face of the sill 20. Such bolts may be utilized for securing the draft arm to the sill and to the bolster as the judgment of the designing engineer may dictate. It is advisable, however, to pass one or more bolts, as 24, 25, vertically through the sills, the bolster members 13 and 14, and the flanges 21 and 23 of the draft arm, thereby 75 80 securely binding these several parts together.

Excessive buffing stresses tend to break the sills of the car upwardly in the line of the bolster. The rearward extension of the draft arm reinforces the sill at this point, 85 and the portion 15 of its extension greatly strengthens this reinforcement, especially as the upper and lower sections are formed integral.

Adjacent the inner end of the draft arm the lower member 15 and its extension is laterally offset, as shown at 26, to extend under the sill 20, and is provided with a depending flange 27 for abutting against a sub-sill 28. This offset portion of the part 15 thus provides a pocket for receiving a tie plate 29 which secures the two draft arms together and extends under both of the sills. Bolts 30 may be set through the sills, the offset portion of the section 15 of the draft arm and the plate 29, thereby still further relieving the sills from the breaking stresses in the line of the bolster by distributing them longitudinally along the sill.

In assembling the parts the upper bolster 105 plate 13 is passed through the apertures in the two draft arms before they are fitted to the car frame. After these parts have been secured in place the lower bolster member 14 is applied.

I claim as my invention—

A draft arm for railway cars comprising a body portion having draft shoulders, and an extension for projecting beyond a body 5 bolster, such extension having a section arching over the bolster and a section passing through the bolster, the lower section being

laterally offset at its inner end to extend under the car sill and form a pocket for a tie plate.

CHARLES C. KINSMAN.
